United States Patent Office.

GEORGE WIGGINS, OF ORTONVILLE, MICHIGAN, ASSIGNOR TO HIMSELF,
CHARLES HERRINGTON, AND HIRAM MAXFIELD, OF SAME PLACE.

Letters Patent No. 77,698, dated May 5, 1868.

IMPROVEMENT IN SHEEP-SHEARING TABLES.

The Schedule referred to in these Letters Patent and making part of the same.

TO WHOM IT MAY CONCERN:

Be it known that I, GEORGE WIGGINS, of Ortonville, in the county of Oakland, and State of Michigan, have invented a new and useful Improvement in Sheep-Shearing Tables; and I do hereby declare that the following is a true description thereof, reference being had to the accompanying drawings, and to the letters marked thereon, and being a part of this specification.

Figure 1 is a perspective view of my table and its attachments.

Figure 2 is a vertical sectional view of the same on the line X X in fig. 1.

The same letters indicate like parts in each figure.

The nature of this invention is to so construct a table upon which to secure sheep while being sheared as to greatly facilitate the operation, enable the operator to readily turn the sheep, when desired, and to prevent the fleece from being soiled.

In order to accomplish this object, I construct a proper frame, A, to sustain the double-inclined top B, which is provided with straps 1, 2, 3, and 4, for the purpose of fastening the sheep to the table, the strap 1 being designed to pass over the sheep, back of the fore legs, while one of the straps, 2, 3, or 4, passes over the neck of the sheep, and is secured to the table by any proper fastening.

The opposite end of the table is provided with the adjustable sliding bar C, operating in its motion parallel with the table, which is furnished with two slots D, in which operate the slides E, upon which the bar C is supported. This bar C is provided with grooves F, in which operate the sliding fastening-blocks G, which are provided with proper straps H, for securing the hind legs of the sheep to be sheared.

The bar C is provided, upon its under side, with a strap, I, which extends to the shaft J, at or near its centre, for the purpose of regulating the position of the bar C, as longer or shorter sheep are being operated upon. The shaft J is provided with a suitable crank, K, and ratchet L, which, with the pawl M, enable the operator to secure the bar C in any desired position.

The sheep being fastened to the table, as hereinbefore described, the sliding fastening-block G' being lower than the similar block G'', will admit, as their position is reversed, of one leg of the sheep passing under, and allow the sheep to be rolled over, as occasion may require.

What I claim as my invention, and desire to secure by Letters Patent, is—

The sliding bar C, in conjunction with the slots D, grooves F, the sliding fastening-blocks G' and G'', the strap I, shaft J, crank K, ratchet L, and pawl M, when arranged and operating substantially as and for the purposes specified.

GEORGE WIGGINS.
